[57] ABSTRACT

An arc-type slip plier having an arcuate lug and arcuate grooves facing the plane of the jaw cavity with the pivotal axis the jaw head portions located between the plane of the jaw cavity and the area of engagement of the arcuate lug and the arcuate grooves.

ARC JOINT PLIER

BACKGROUND AND SUMMARY OF INVENTION

This invention relates to an improvement in an arc-type slip plier which has conventionally been provided with an arcuate lug and arcuate grooves which face away from the plane of the jaw cavity so as to define a pivotal axis located a substantial distance further beyond the plane of the jaw cavity than the area of engagement between the arcuate lug and the arcuate grooves. In the present invention, the arcuate lug and arcuate grooves face toward the plane of the jaw cavity with the pivotal axis located at or between the plane of the jaw cavity and the area of engagement between the arcuate lug and the arcuate grooves.

BRIEF DESCRIPTION OF THE DRAWING

FIG. 1 is partial side elevational view of a conventional arc-type plier; and,

FIG. 2 is a partial side elevational view of a new and improved arc-type plier.

DETAILED DESCRIPTION OF THE INVENTION

Referring first to FIG. 1, a conventional arc-type plier 10 is shown to comprise an upper jaw member 12 having a jaw head portion 14, with a relatively flat gripping surface 16 thereon, and a handle portion 20, only a portion of which is shown, extending transversely relative to the jaw head portion. A lower jaw member 22 is provided with a jaw head portion 24, having a relatively flat gripping surface 26 thereon, and a handle portion 28, only a portion of which is shown, extending transversely relative to the jaw head portion. Arc-type groove means are provided on one handle portion 20 by a series of grooves 30 extending along arcs having their centers located a substantial distance below the jaw cavity 32 along the centerline 34 of pivot pin slot 36 which is centrally formed in handle portion 20. Arc-type lug means are provided on the other handle portion 28 by a lug member 38 extending along an arc having its center located a substantial distance below the jaw cavity along the centerline 34. A conventional connecting means (not shown) secures the jaw members in assembled position with a pin portion (not shown) extending through an opening 40, in the other jaw handle 28, which opening is in spaced relationship to the lug member 38 along centerline 34 and through the aligned slot 36. The arrangement is such as to permit the arcuate lug 38 to be selectively placed in any one of the arcuate grooves 30. In the uppermost position of FIG. 1, the pivotal axis 42 is spaced from a plane 44, including the gripping surface 26, (sometimes referred to hereinafter as the plane of the jaw cavity) by a substantial distance x with the result that the outermost point 46 of lower jaw head portion 24 moves outwardly relative to upper jaw head portion 14 along an arc 48 a distance y which can be somewhat disadvantageous in attempting to use the tool in confined circumstances. More importantly, the prior art arrangement is such as to cause the fulcrum to lie in a plane 50 extending obliquely relative to the gripping surface 26 resulting in unequal distribution of gripping forces therealong.

Referring now to FIG. 2, wherein similar parts are referred to by the same numbers, the arcuate grooves 30 and arcuate lug 38 have been reversed so as to face the plane of the jaw cavity with the arcuate centers of the grooves and lugs as well as the pivotal axis of the jaw

portions being located on the plane of the jaw cavity in the uppermost lug position and located between the lug and the plane of the jaw cavity in all other positions. In this manner, the distances x and y are reduced, to approximately zero in the uppermost lug-groove position, with point 46 remaining behind the vertical plane 50, which includes the outermost point on the upper jaw portion 14, as the point 46 is variously located along arc 48. In addition, the plane of the fulcrum 50 is substantially coincident or parallel with the plane of the jaw cavity in the gripping position.

Thus, although the new and improved structure comprises a reversal of known structure, new and improved results are obtained which provide improved operating characteristics.

I claim:

1. An arc joint slip-type plier tool comprising:
a first jaw member having a jaw head portion with an elongated gripping surface thereon and a handle portion extending generally transversely therefrom,

a second jaw member having a jaw head portion with an elongated gripping surface thereon and a handle portion extending generally transversely therefrom,

the elongated gripping surfaces on said first jaw member and the elongated gripping surface on said second jaw member facing one another in generally parallel relationship and defining a jaw cavity therebetween terminating inwardly and closed adjacent the handle portions and terminating outwardly in a jaw cavity opening defined by terminal transverse outer surfaces of said jaw portions,
an elongated slot in one of the handle portions extending at substantially a right angle to the elongated gripping surfaces and defined by spaced parallel side surfaces on opposite sides of a central longitudinal axis of said slot,

pivot pin means slidably rotatably mounted in said slot between said spaced parallel side surfaces and pivotally connecting the handle portions for pivotal movement relative to one another between an open jaw cavity position and a closed jaw cavity position and slidably connecting the handle portions for sliding adjustment along said slot to variably adjusted positions to vary the spacing between the elongated gripping surfaces in the closed jaw cavity position,

said pivot pin means having a pivotal axis extending transversely of and located in general coplanar relationship with said central longitudinal axis of said slot and with said elongated gripping surface on said second jaw portion in all of said variably adjusted positions,

an arc-type lug means on one of the handle portions and located and spaced axially along said central longitudinal axis of said slot from said pivot pin means beyond said jaw cavity and having a radius of curvature extending toward and coaxial with said pivotal axis of said pin means,

a plurality of arc-type groove means on the other of the handle portions each being separately slidably rotatably cooperable with said arc-type lug means and having a radius of curvature extending toward said pivotal axis of said pin means and having a radius of curvature of equal length to the length of the radius of curvature of said arc-type lug means,

said pin means and said pivotal axis provided thereby being movable along said slot to a plurality of variably displaced positions whereat said arc-type lug means is slidably rotatably cooperably associated with various separate ones of said arc-type groove means for relative rotatable sliding movement about said pivotal axis of said pivot pin means, the transverse terminal outer surfaces of said jaw portions being substantially aligned and coterminous in each of said adjusted positions when the jaw portions are in the closed jaw cavity position and the path of relative movement of said transverse terminal outer surfaces of said jaw portions in each of

said adjusted positions during movement between said closed jaw cavity position and said open jaw cavity position being arcuate about said pivotal axis of said pin means whereby the distance between said terminal transverse outer surfaces of said jaw portions and the central longitudinal axis of said slot in any open jaw cavity position is always equal to or less than the distance between said terminal transverse outer surfaces of said jaw portions and the central longitudinal axis of said slot in said closed jaw cavity position.
